CORRUGATED CARDBOARD FOR PACKING PURPOSES.

1,065,639.

Specification of Letters Patent. Patented June 24, 1913.

Application filed April 1, 1903. Serial No. 150,660.

To all whom it may concern:

Be it known that I, CAMILLE THIÉBAUT, a citizen of the French Republic, residing at 268 Avenue Daumesnil, Paris, France, have invented certain new and useful Improvements in Corrugated Cardboard for Packing Purposes, of which the following is a specification.

This invention relates to improvements in 10 corrugated cardboard.

Plaited, waved or corrugated cardboards as hitherto manufactured do not present sufficient rigidity for large packages. It is true that in some cases there has been stuck 15 to one or both sides of sheets of corrugated cardboard a smooth sheet uniting all the corrugations situated upon the same side, but the product so obtained is expensive, inextensible and only imperfectly resists 20 compression exerted at right angles to the original plane surface of the corrugated sheet.

The conditions which should be fulfilled by corrugated cardboard are as follows: 25 1. The cost price should be exceedingly small. 2. The weight should be as small as possible. 3. The cardboard should present the greatest possible resistance to the efforts 30 of compression which it may have to support either in the direction of the original plane surface before corrugation, or at right angles to this plane. 4. Constant extensibility for the purpose of permitting the cardboard to be shaped as regularly as possible to the objects to be packed and of causing 35 it to assume the form of packages of the most various kinds, such as flagons or bottles. In my novel corrugated cardboard all these conditions are fulfilled.

40 In the accompanying drawing: Figure 1 is a section on the line A—B of Fig. 2. Fig. 2 is a plan view of my novel corrugated cardboard. Fig. 3 is an elevation of the fluted shaft for driving the endless chains in a machine for making this cardboard. Fig. 4 is a plan view showing the relative positions of the fluted shaft and the endless chain of said machine, and Fig. 5 is a sectional view of said machine showing 45 two endless chains pressing a sheet of cardboard.

In chain machines employed in the production of corrugated cardboard, the driving is effected by means of gear wheels cast upon a shaft. When the paper or other

substance to be treated is of small thickness, the folds or undulations are produced without difficulty, but when the substance to be treated is of any considerable thickness, the blades of the chains which are only supported at a few points in their length cannot sufficiently support the effort which they must overcome, this effort consisting in forcing the cardboard to assume the profile of the blades of the chains without rupture. 60

In this machine the driving shafts *a* are provided with grooves throughout their entire length, in such a manner as to produce the driving of these chains *b* equally throughout their width and a corrugated 70 cardboard is produced which presents all the characteristics herein enumerated.

This novel cardboard is provided in the usual manner with corrugations which are formed alternately above and below the 75 original plane of the sheet but instead of being smooth and continuous throughout their length these corrugations are formed with protuberances, ribs or projections *f* at greater or less intervals one from the other, which so to speak convert each of the folds, undulations or corrugations into a reinforced beam, and the sheet of cardboard as a whole into a series of rigidly connected reinforced beams. It will be readily understood that 80 these protuberances impart to the corrugations considerable capacity for resisting pressure which may be exerted in a direction at right angles to the original plane of the sheet of cardboard and that they render unnecessary the employment of the auxiliary sheet of cardboard stuck to the summits of each of the corrugations which has been referred to above. The absence of this reinforcing sheet results in a diminution of 85 weight and reduction of the cost of manufacture, since the protuberances in question are obtainable in a single pressing operation. These protuberances also impart to the sheet 90 perfect extensibility and permit it to adapt itself to all kinds of packages. In other words, a sheet of corrugated cardboard is produced with corrugations extending substantially in a line from one edge of the sheet to the other, the walls of the corrugations extending substantially perpendicular 100 to the plane of the sheet, and each provided with a series of reinforcing protuberances projecting substantially at right angles to the wall, and also there is produced corrugations 105

110

gated cardboard having parallel longitudinal corrugations extending substantially in a line from one edge of the sheet to the other, the walls of the corrugations extending substantially perpendicular to the plane of the sheet, and each provided with a series of reinforcing protuberances projecting at substantially right angles to the walls, the corrugations being of less elevation above the median plane of the sheet than the distance between the corrugations of the sheet.

Cardboard of this kind would in some cases leave an impression upon the articles to be packed; in this event it may obviously be provided with a plain protecting sheet. It may also happen in certain cases where only weight is a consideration, for example where it is desired to replace a wooden packing, that one or two plane auxiliary sheets may be added (one on each side) to this improved cardboard. In this manner sheets of great lightness are obtained which are perfectly able to resist compression in the longitudinal direction of the corrugations and also compression exerted at right angles to the planes of the walls.

My improved cardboard, the corrugations of which are provided with protuberances, offers considerable advantages as regards cost of production. As compared with cardboard formed with continuous and smooth corrugations and provided with an auxiliary reinforcing sheet, a sheet of my improved cardboard of much less thickness and consequently of less weight per square meter will be of equal strength, owing to the provision of the protuberances on the corrugations.

It is therefore apparent that the cost price, of this novel article is considerably lower than that of ordinary corrugated cardboards.

Having now particularly described and ascertained the nature of my said invention and in what manner the same is to be performed, what I claim is—

1. As a new article of manufacture, a sheet of corrugated cardboard having corrugations extending substantially in a line from one edge of the sheet to the opposite edge thereof, the walls of the corrugations extending substantially perpendicular to the plane of the sheet and each being provided with a series of reinforcing protuberances projecting at substantially right angles to the walls.

2. As a new article of manufacture, corrugated cardboard having parallel longitudinal corrugations extending substantially in a line from one edge of the sheet to the other, the walls of the corrugations extending substantially perpendicular to the plane of the sheet and each being provided with a series of reinforcing protuberances projecting at substantially right angles to the walls, the corrugations being of less elevation above the median plane of the sheet than the distance between the corrugations of the sheet.

In witness whereof I have hereunto set my hand in presence of two witnesses.

CAMILLE THIÉBAUT.
